UNITED STATES PATENT OFFICE.

SAMUEL A. VAN OSDEL, OF JOHNSON, NEBRASKA.

SURGICAL INSTRUMENT.

Application filed October 6, 1920. Serial No. 415,031.

To all whom it may concern:

Be it known that I, SAMUEL A. VAN OSDEL, a citizen of the United States, and a resident of Johnson, county of Nemaha, 5 State of Nebraska, have invented certain new and useful Improvements in Surgical Instruments, of which the following is a specification.

This invention relates to surgical instruments and is herein embodied in an instrument of special utility in removing enlarged or diseased tonsils or the like, it being understood that by simple modifications it may be adapted to other uses without departing 15 from the spirit of the invention.

In removing tonsils it is desirable to crush the tissue and blood vessels back of the capsule of the tonsil where the tonsil joins the faecal pillars of the throat, and 20 to hold them tightly for a time, whereby the macerated walls of the blood vessels are caused to stick together, blood clots can form and the hemostatic action is otherwise greatly increased. A powerful crushing action 25 is necessary to produce this effect, and the pressure exerted must be sustained for a time, after which the tonsil may be cut from the crushed stump, leaving a layer of macerated tissue on the surface of the stump.

30 One of the objects of this invention is the provision of an instrument by which a powerful crushing action may be exerted and sustained, and by which the crushed member may be severed by a distinct cutting 35 action.

Another object is the provision of an instrument of this type which can be efficiently operated with one hand, and which is of simple construction so that it may be 40 readily disassembled and cleaned.

A further object is the provision of an instrument of this type which will facilitate the sight of the operation by the operator, and which can be operated with a minimum 45 of inconvenience to the patient.

Still further objects of the invention and the features of novelty will be apparent from the following specification when taken in connection with the accompanying drawings in which:

Figure 1 is a side elevation of an instrument embodying my invention.

Fig. 2 is a fragmentary plan view of the instrument shown in Fig. 1, part being 55 broken away to show more clearly the construction of the parts.

Fig. 3 is a fragmentary vertical longitudinal section of the structure shown in Fig. 1.

Fig. 4 is an enlarged transverse section taken on line 4—4 of Fig. 1, looking in the 60 direction of the arrows.

Fig. 5 is an enlarged fragmentary longitudinal section on the line 5—5 of Fig. 2.

Fig. 6 is a vertical transverse section on the line 6—6 of Fig. 1, looking in the direction of the arrows, and

Fig. 7 is a fragmentary side elevation of a modified form of the instrument, the parts being shown as having been operated to closed position.

The instrument shown in the drawings comprises a frame 11 having a handle 12 rigid therewith and extending at an angle from the rear end of the frame. A cutting blade 13 is slidably carried by the frame, 75 and is provided with a projection, or trigger 14, which extends through a slot 15 in the frame. The forward end of the frame is broadened, as shown in Fig. 2, the corresponding portion of the blade 13 being also 80 broadened and having an opening therein to form longitudinally extending lateral portions 16, and a slightly curved, transverse end portion 17, the lower side of which is beveled as shown at 18 in Fig. 5 to form a 85 sharp cutting edge. Adjacent its forward end the forward end of the frame is curved upwardly and forwardly to extend through the opening in the cutting blade 13, slots 19 being formed at the sides of the upwardly 90 extending portion to receive the lateral portions 16 of the cutting blade 13, that part of the frame 11, however, which lies above the cutting blade, being wider than the opening in the cutting blade 13 as shown at 20 in 95 Fig. 2, so that the forward end of the blade 13 is held from movement away from the frame. The opening in the cutting blade is long enough to permit the widened end of the forward end of the frame member to 100 be inserted therethrough after which the cutting blade may be rotated to position the lateral portions 16 in the slots 19 of the frame, and be then swung downwardly into engagement with the frame, the trigger 14 105 entering the slot 15 in the frame.

A hemostat member 21 is slidably carried by the frame and is spaced therefrom by the cutting blade 13, being widened at its forward end to conform to the shape of the 110 corresponding portions of the frame and the cutting blade 13. This widened portion is

extended downwardly at the sides of the widened portion of the frame and cutting blade, and then inwardly, as shown in Fig. 4 to provide ledges 22, which engage the under side of the widened end of the frame. The member 21 and the cutting blade 13 are thus held in assembled relation on the frame and are guided in their reciprocatory movement relative thereto and relative to each other, a part 23 of each ledge 22 being raised to underlie and guide the cutting blade 13, as shown most clearly in Fig. 5.

An opening 24 is formed in the widened end of the hemostat member 21, similar to that in the cutting blade 13, leaving a slightly curved transverse portion 25 connected to the body of the member 21 by the channel shaped longitudinally extending lateral portions which constitute the guiding means. The transverse end portion 25 is undercut at 26, as shown in Fig. 5 to receive the end of the frame 13 when the parts are moved to operated position. That part of the opening 24 in the member 21 which is forward of the raised end of the frame 13 constitutes a fenestra and, as the member 21 is retracted on the frame, the portion 25 will co-operate with the abutment at the end of the frame to crush and distort the tissues of the tonsil or other member which is to be removed. A slot 27 is formed in the hemostat member 21 into which a pin 28 on the cutting blade 13 extends, whereby the rear end of the member 21 is held from lateral movement relative to the frame. The pin 28, as well as the trigger 14 may be integral with the blade 13, or may be secured thereto by riveting or welding or in any other suitable manner, and it will be apparent that the pin and trigger may be formed in one piece and then suitably secured to the blade 13, if desired.

A lever 29 is provided for retracting the hemostat member 21, being mounted for pivotal movement on the frame 13 so as to swing toward and from the handle 12. This lever is preferably stamped from metal of uniform thickness and has a back 30 from which side flanges 31 are bent to make the body of the lever channel shaped in cross section, thereby increasing its rigidity.

The side flanges 31 are extended as shown at 32, such extensions having rounded ends 33 which are pivotally received in open ended recesses 34 which are formed in the sides of the handle 14 where it joins the frame 13. The side flanges 31 are also extended as shown at 35, such extensions being bent toward each other at 36 and provided with rounded ends 37 which are received in circular recesses 38 in the sides of the enlarged rear portions 39 of the hemostat blade 21. As shown at 40, in Figs. 1 and 6, the lateral surfaces of the rear por-

tion 39 of the member 21 are inclined, to facilitate springing the extensions 35 apart to permit the circular ends 37 to snap into the recesses 38.

A flat spring 41, curved as shown in Fig. 3, is mounted on the rear of the handle 12, the handle having a lug 42 thereon which is provided with laterally extending lips, and the spring having an elongated slot 43 therethrough, so that the spring may be placed in position on the lug 42 and rotated about it to the position shown, when the lips on the lug will overlie the spring and hold it in place. It will be understood that the spring 41 is sufficiently resilient to permit it to be positioned between the side portions of the handle 12 and the flanges 31 of the lever 29.

In assembling the instrument the cutting blade 13 is mounted on the frame 11 as previously described, and retracted so that its trigger 14 engages the rear end of the slot 15, and its sharpened end portion 17 underlies the upwardly deflected end of the frame. The hemostat member is then slid rearwardly so that the channel shaped lateral portions of its forward end envelop the widened ends of the cutting member 13 and the frame 11, there being sufficient play to permit the rear end of the member to ride on the pin 28 until the slot 27 registers therewith. The spring 41 is then put in place on the handle 12 as described, the lever 29 is placed in position with the rounded ends 33 in the recesses 34, and the lever is pivotally connected to the hemostat member 21 to hold the parts in assembled relation, by engaging the circular ends 37 with the inclined surfaces 40 to force them apart and permit them to snap into the recesses 38.

In the modified form of instrument shown in Fig. 7 the end of the lever 29^a is formed with side flanges 44 which engage on opposite sides of an upward extension 45 on the hemostat blade 21^a, a screw 46, or other suitable detachable member, passing through the flanges 44 and the extension 45 to pivotally connect the parts. The parts are assembled in the same manner, the screw 46 being inserted after the lever 29^a is placed in position, to hold the parts in assembled relation.

The instrument is operated while supported in either hand, it being so held that the forefinger is in position to engage the trigger 14 and the other fingers engage the handle 12. When the instrument has been properly positioned relative to the tonsil or other member to be severed, so that such member extends through the fenestra between the end portion 25 of the hemostat member 21 and the abutment at the end of the frame 11, and protrudes through the opening in the cutting blade 13, the hemo-

stat member is retracted to exert a powerful crushing action by gripping the lever 29 and the handle 12. The pressure on these members is sustained to hold the tissues and blood vessels in a crushed state and after a suitable lapse of time the cutting blade 13 is retracted by engagement of the forefinger of the hand which holds the instrument with the trigger 14; the sharpened edge of the cutting blade passing close to the corner at the lower side of the extreme end of the frame 11. If it is desired to use the crushing blade alone, the cutting blade 13 may be first retracted so that the cutting edge underlies the end of the frame.

It will be noted that, in the operation of the instrument, the centers of the circular ends 37 pass over the centers of the rounded ends 33 in the recesses 34. The spring 41 normally tends to hold the rounded ends 33 against the upper end walls of the recesses 34. When the instrument is in use however, the lever 29 tends to swing about the line joining the centers of the circular ends 37, and the rounded ends 33 are held against the forward walls of the recesses 34 and roll down such walls, so that the hemostat blade 21 will be held toward the frame 11. During part of the movement the tendency to roll will be prevented and the ends 33 will slide upwardly on the forward walls of the recesses 34.

The instrument comprises but few parts, and these are of simple construction and can be readily disassembled and cleaned. It can be effectively operated by either hand alone, affording a powerful crushing action and an independent cutting action, neither of which requires the use of the other hand. The danger of the instrument slipping or twisting with consequent injury to the patient, is much less than it is with an instrument which requires the co-operation of both hands; and the relative sliding parts are held together, thus obviating the danger of catching and pinching the parts against which the side of the instrument is engaged.

While the structure and operation of certain embodiments of the invention have been shown and described it will be understood that changes may be made in the details of construction without departing from the spirit of the invention which is defined in the appended claims.

The invention having been thus described, what is claimed is:

1. A surgical instrument comprising a frame member having an abutment thereon and a handle rigid therewith, a crushing blade and a cutting blade slidably carried by said frame and means for retracting said crushing blade and said cutting blade toward said handle to cause them to co-operate with said abutment.

2. A surgical instrument comprising a

frame, a secondary co-operating member slidably carried by the frame, a cutting blade between said frame and said secondary co-operating member and having an opening therein through which a portion of the frame extends, said secondary co-operating member guidingly engaging said frame and having an abutment for co-operation with the end of the frame, and means for retracting said secondary co-operating member and said cutting blade.

3. A surgical instrument comprising a frame member having a handle rigid therewith, a secondary member having an abutment for co-operation with the end of the frame member, a blade having a cutting edge adapted to co-operate with the end of said frame, and independent means operable by the hand engaging said handle for retracting said blade and said secondary member to move said abutment and the cutting edge of said blade toward the forward end of the frame.

4. A surgical instrument comprising a frame member having a handle rigid therewith and a terminal abutment at its forward end, a secondary co-operating member having a fenestra at its forward end and guided for sliding movement relative to said frame to co-operate with said abutment when retracted, a cutting blade having a fenestra at its forward end, means for retracting said secondary co-operating member, and means for retracting said cutting blade.

5. A surgical instrument comprising a frame member having a handle rigid therewith, a secondary co-operating member and a cutting member carried by said frame, said cutting member having an opening therethrough at its forward end through which the end of the frame extends so that the end of said cutting blade when in retracted position underlies the end of the frame, and means for retracting said secondary co-operating member and said cutting member.

6. A surgical instrument comprising a frame member having an abutment at its forward end, and a cutting blade having an opening at its forward end, said frame extending through the opening of the blade and having a laterally extended portion overlying said blade at the side of the opening, and means for sliding said cutting member relative to said frame.

7. A surgical instrument comprising a frame having a handle rigid therewith and having an abutment at its forward end, a secondary member slideable relative to said frame and having a transverse portion adapted to co-operate with said abutment, and a lever to the rear of said handle and having a rolling pivotal connection with said frame for moving the transverse portion of the secondary member toward the

abutment of the frame and yieldably holding said member toward said frame as said lever is swung toward said handle.

8. A surgical instrument comprising a frame having an abutment thereon and having a handle rigid therewith disposed at an angle relative thereto, a secondary member 5 slideable relative to said frame and having a portion adapted to co-operate with said abutment, and a lever for operating said secondary member, said lever being of substantially uniform thickness throughout and having forwardly bent lateral portions slidably and pivotally received in slots in the 10 sides of said handle.

9. A surgical instrument comprising a frame having a handle rigid therewith and an abutment thereon, a secondary member 15 slideable relative to said frame and having a portion thereof adapted to co-operate with said abutment, and a lever for operating said secondary member, said lever having a laterally yieldable extension engaging said sec-

ondary member to afford a releasable pivotal connection therewith.

10. A surgical instrument comprising a frame having an abutment thereon and having a handle rigid therewith disposed at an angle relative thereto, a secondary member 20 slideable relative to said frame and having a portion adapted to co-operate with said abutment, and a lever for operating said secondary member, said lever being of substantially uniform thickness throughout and having lateral portions bent forwardly and 25 pivotally received in openings in the frame and having a portion pivotally and releasably connected to said secondary member.

11. A surgical instrument comprising an apertured member, means for clamping the 30 part protruding through said aperture, and a severing blade movable adjacent to said clamp in a direction toward the operator to sever the protruding part.

In testimony whereof I affix my signature.

SAMUEL A. VAN OSDEL.
